INFANT'S SAFETY COVERING

Frederic Comyns, Dumont, N. J.

Application August 7, 1947, Serial No. 766,993

1 Claim. (Cl. 128—134)

1

The present invention relates to a blanket or bed covering for infants so designed as to make it possible for the infant to move about in its crib or bed without hampering its movements and without becoming uncovered.

In the past numerous types of infant's coverings and garments have been devised and intended to provide for freedom of movement of the infant while at the same time providing for the comfort and warmth of the infant.

The present structure while similar in some aspects to those previously devised is much simpler in utilization and is at the same time readily and economically manufactured.

The structure of my present invention comprises a vest which is worn over the usual sleeping garment in combination with a blanket or the like and a strap so arranged that the infant may turn and have freedom of movement but is prevented from moving about to a sufficient extent to cause the bed covering to get into a position over the baby's face and thus cause suffocation.

It is an object of the invention to provide a bed covering for an infant so designed as to prevent the infant from kicking or otherwise causing the blankets to move in a position over its face.

It is another object of the invention to provide such a covering which permits freedom of movement of the baby.

It is a further object of the invention to provide such a covering which assures that the baby is at all times completely covered and completely comfortable.

Other objects and features of the invention will appear when the following description is considered in connection with the annexed drawings in which—

Figure 1 is a perspective view showing the cover in use on a baby's crib;

Figure 2 is a top plan view of the cover itself illustrating particularly the fact that the upper edge thereof is provided with an elastic tape in order to increase the degree of freedom of movement of the infant when the covering is in use;

Figures 3 and 4 are, respectively, front and rear elevations of a vest which is used in combination with the covering of Figures 1 and 2;

Figure 5 is a detailed view taken on the plane of the line 5—5 of Figure 4 and illustrating a belt loop which is attached to the vest at the rear thereof;

Figure 6 illustrates a belt such as may be used with the vest and covering; and

2

Figure 7 is a fragmentary, transverse, cross-sectional view of the crib of Figure 1 showing the relationship of the baby, vest, belt and covering.

Referring now to the drawings, there is shown 5 at 10 a crib of conventional type which is provided with the mattress 11 and in which a baby 12 is illustrated, the baby being covered with the covering of my invention here designated 13. As is clearly seen in Figure 2, the covering 13 has an elastic tape 14 at its upper edge and is made in a trapezoidal form such that when the elastic is fully contracted as shown in Figure 2 the covering 13 appears to be rectangular. As is clearly shown in Figures 1 and 2, the covering 13 is provided with tapes 15 at its corners, which tapes may be tied about the posts and side rails of a crib or other convenient portions of the crib in the manner illustrated in Figure 1.

The bed covering already described is designed 20 to be utilized in connection with a vest 16 (Figures 3 and 4) which vest is put on the infant over its normal sleeping garments and is fastened in the front by means of the usual buttons 17.

The vest 16 is provided with a belt loop 18 25 which is fixed to the vest on the center line of the rear portion thereof and spaced somewhat from the lower edge. In fact, the belt loop 18 may, in some instances, be placed at substantially the center of the rear portion of the vest. This belt loop cooperates with a belt such as that shown at 20 (Figure 6) to hold the infant in place with respect to the covering 13 and, of course, the crib 10 and mattress 11.

Referring to Figures 2 and 7, it will be seen 30 that the cover 13 is provided with the two openings 21 through which the belt 20 is passed. As is clearly seen in Figure 7, the belt 20 is passed through one of the openings 21, encircles the baby passing through the belt loop 18 of the vest 16, and is then brought out through the other of the openings 21 and buckled by means of the conventional buckle 22 cooperating with the holes 23.

It will be seen that due to the arrangements 45 described, it will be impossible for the infant to move upwardly and thus to become uncovered. Additionally, due to the utilization of the vest as described, it will be impossible for the infant to, 50 by kicking or otherwise, either move downwardly with respect to the cover or cause the cover to move upwardly to cover its face and thus all danger of suffocation is eliminated. At the same time the child may roll about as much as is desirable since the only limitation upon such move-

ment is that he cannot move through a complete turn but is limited to a degree of movement corresponding to the major circle arc along the belt between the two openings 21. Further, by utilization of the elastic tape 14 or by otherwise elasticizing the top of the covering 13, freedom of movement is enhanced since this provides a surplus of material which permits a sidewise shifting of the infant upon the crib.

The device of this invention may also be used without the vest in some instances. Thus the blanket with the strap but without the vest may be utilized to hold the infant in position in a carriage, the blanket in this instance being somewhat smaller than when used in a crib. If desirable a loop may be provided on the carriage mattress or sheet to cooperate with the belt or a large safety pin may be used as a belt loop being fastened to the carriage mattress or sheet. Also when the infant has grown so that there is no longer danger of suffocation, the blanket may be utilized alone merely as a covering and will not have to be discarded or the blanket and belt may be utilized to retain the infant in a preferred position but with somewhat less security than is afforded when the vest is also used.

While I have described a preferred embodiment of my invention, it will be understood that the foregoing description is illustrative only and, therefore, I wish to be limited not by the description but solely by the appended claim.

30

What is claimed is:

An infant's safety sleeping device comprising a vest to be worn by an infant over its normal sleeping garment, a belt loop on said vest, said belt loop being located at the rear of said vest, said belt loop being located at the rear of said vest approximately on the longitudinal center line thereof and being located substantially one-quarter of the distance from the bottom of said vest to the top thereof; a covering provided with an elasticized upper edge, said covering having a pair of apertures therein adjacent the upper edge thereof and spaced on either side of the longitudinal center line, securing means fastened to the corners of said covering for securing said covering to the infant's bed, and a belt passing through said openings in said cover and said loop in said vest to thereby assure the infant being covered at all times while at the same time free to move about.
